UNITED STATES PATENT OFFICE.

VICTOR H. HARBERT, OF SPRINGFIELD, ILLINOIS, ASSIGNOR TO E. PAYSON SMITH, OF CHICAGO, ILLINOIS.

BRACKET FOR RETAINING VALVES.

Application filed September 8, 1925. Serial No. 55,195.

Retaining valves are applied to cars to make the movement of a train of cars safe, and to conserve the supply of air, and this valve when set and in good working order does not allow all of the air to escape from the brake cylinder, but retains a certain amount of pressure therein sufficient to hold the brakes in a set position, while the air is being replenished in the train line. When the air pressure in the line is increased or replenished, if the retaining valve is in an inoperative condition, the triple valve will automatically assume a released position allowing the train to gain momentum, and run out of control. It is, therefore, of the utmost importance that the retaining valve be in good working order at all times.

Bolts are used so as to attach retaining valves to the car under the old practice, the head of the bolt being on the inside of the car. When a retaining valve fails, if the car is moving under load, it is necessary to break the seals of the car in transit to remove the load from the end of the car to get at the bolts for the purpose of removing and replacing the retaining valve. When the car is loaded with valuable freight, the handling and moving of the same has resulted in costly damage claims, due to workmen's carelessness, their failure to replace the freight in safe condition and location for movement on to destination.

Retaining valves have to be removed frequently and with the practice generally in vogue the bolts holding the valve to the car become loose, and it is impossible to again tighten the nuts as the bolts will turn unless held by a workman on the inside of the car, all of which is, as above pointed out, very objectionable.

It is often the case that under service conditions the retaining valve pipe breaks loose at the threads where it enters the retaining valve, this being the weakest point. It is then necessary to replace the said pipe of the full length from the union to the valve, which is about 20 feet long on closed cars and about 15 feet long on open type cars.

One of the objects of my invention is to provide an anchor, or bracket permanently secured to the car to which the retaining

valve may be secured to and detached from without entering the car.

Another object of my invention is to provide a connection between the anchor and retaining valve which will permit of varying lengths of pipe (within a reasonable limit) for the retaining valve without disturbing the original position of the anchor.

Other objects of my invention will readily be suggested to those skilled in this art.

In the drawings:

Figure 1 is a front elevation of my anchor with a retaining valve attached thereto.

Figure 2 is a side elevation of Figure 1. 65

Figure 3 is a front elevation of my anchor.

Figure 4 is an end elevation of Figure 3.

Figure 5 is a bottom plan view of Figure 3.

The reference numeral 1 designates the retaining valve air pipe to which the retaining valve 2 is secured, the connection being a threaded one.

My improved retaining valve anchor, or bracket, comprises a head 3 having suitable bolt or rivet openings 4, through which bolts or rivets pass to secure the anchor to the car 5 permanently. A stem 6 intermediate the ends of the head depends from the head and is in the plane of the head to increase the surface contact between the anchor and the car. On each side of the stem 6 is a shelf 7 integral with and depending from, and extending forwardly of the head 3 from the outer edge of which is a depending apron 8 which is connected to the stem 6 by the spacing wall, or plate 9. 80

The apron 8 is provided with an elongated slot which, at its upper end, opens into the bolt head opening 11 through the shelf 7, as clearly shown in the drawings. 90

The anchor being secured to the car, the workman, if he prefers, can slip the bolts 12 into the opening 11 and slots 10 and then position the retaining valve on said bolts by aligning the bolt openings usually provided in the lugs 14 of the anchor and then tightly screw the nuts 15 on the bolts 12 thereby securely and firmly locking the retaining valve to the anchor. 95

In the first installation, the bolts 12 would be positioned near the tops of the slots 10, so that they could be lowered in the slots

if need be to compensate for any shortening of the air pipe 1, thereby obviating the necessity of changing the anchor from its original position.

5. What I claim is:

A retaining valve bracket comprising a head, a stem depending from and in the plane of the head, a shelf on each side of the stem integral with and depending and extending

forwardly from the head, an apron depending from the outer edge of said shelves, and a plate connecting the aprons with said stem, a bolt opening through each of said shelves, and an elongated slot in each of said aprons opening into said bolt holes.

10. In testimony whereof I affix my signature.

15. VICTOR H. HARBERT.
